(57) **CLAIM**

The ornamental design for a packaging container, as shown and described.

DESCRIPTION

FIG. 1 is a Perspective view of a packaging container according to one embodiment of the new design.

FIG. 2 is an elevational view of a Back thereof.

FIG. 3 is an elevational view of a Front thereof.

FIG. 4 is an elevational view of a Left thereof.

FIG. 5 is an elevational view of a Right thereof.

FIG. 6 is a plan view of a Top thereof.

FIG. 7 is a plan view of a Bottom thereof.

FIG. 8 is a Perspective view of a packaging container according to another embodiment of the new design.

FIG. 9 is an elevational view of a Back thereof.

FIG. 10 is an elevational view of a Front thereof.

FIG. 11 is an elevational view of a Left thereof.

FIG. 12 is an elevational view of a Right thereof.

FIG. 13 is a plan view of a Top thereof.

FIG. 14 is a plan view of a Bottom thereof.

FIG. 15 is a Perspective view of a packaging container according to yet another embodiment of the new design.

FIG. 16 is an elevational view of a Back thereof.

FIG. 17 is an elevational view of a Front thereof.

FIG. 18 is an elevational view of a Left thereof.

FIG. 19 is an elevational view of a Right thereof.

FIG. 20 is a plan view of a Top thereof; and,

FIG. 21 is a plan view of a Bottom thereof.

The broken lines depicted in FIGS. 15-20 are for illustrative purposes only and forms no part of the claimed design.
